UNITED STATES PATENT OFFICE.

JOHN S. WOODBRIDGE, OF DETROIT, MICHIGAN.

PAPER-BOX MACHINE.

SPECIFICATION forming part of Letters Patent No. 739,529, dated September 22, 1903.

Application filed November 10, 1902. Serial No. 130,640. (No model.)

To all whom it may concern:

Be it known that I, JOHN S. WOODBRIDGE, a citizen of the United States, residing at Detroit, county of Wayne, State of Michigan, have invented a certain new and useful Improvement in Paper-Box Machines; and I declare the following to be a full, clear, and exact description of the invention, such as will enable others skilled in the art to which it pertains to make and use the same, reference being had to the accompanying drawings, which form a part of this specification.

My invention relates to an improvement in paper-box machines, shown in the accompanying drawings and more particularly set forth in the following specification and claims.

Referring to the drawings, Figure 1 is a plan view of the machine. Fig. 2 is an end elevation. Fig. 3 is a cross-sectional view through the receiving-pockets and showing the same supported in the channel iron or way provided for that purpose. Fig. 4 is a perspective view of one of the segments containing the receiving pockets or dies. Fig. 5 is a plan view of a detail, showing parts in section, disclosing more particularly the means employed for locking the receiving-pockets in position under the plunger and also the means for moving the receiving-pockets successively under said plunger. Fig. 6 is a cross-sectional view on the line $\alpha\alpha$ of Fig. 5.

My invention contemplates a construction wherein a series of receiving pockets or dies are successively moved in position under the forming die or plunger to receive the newly-formed box, which is allowed to remain in the pocket until thoroughly dried, when it is discharged.

The particular feature of the invention consists in providing a closed channel in which the receiving-pockets travel for the purpose of presenting a solid base, against which the forming-die forces the paper, thereby insuring the box having sharply-defined corners and squarely-formed side and end walls. This is not possible where the paper is forced into a die open at the base.

Another feature of the invention is the means employed for locking the receiving-pockets under the forming-die and also the mechanism employed to move the pockets successively into position.

Another feature of the invention is the manner of constructing the forming die or plunger in two parts for the purpose of taking up any wear that may occur in the plunger and to provide a minute adjustment of the parts.

Referring to the letters of reference shown on the drawings, A is the frame of the machine; B the main driving-shaft, and B' the driving-pulley.

C is one of the reels over which the paper is fed in its passage to the forming-dies.

D is a cam mounted on the driving-shaft 65 for operating the gluing mechanism D'.

E is a cam mounted on the driving-shaft for operating the slitting-die E'.

F is a cam mounted on the driving-shaft for operating the cutting-off die, and G is a cam controlling the fingers G', designed to fold the ends of the side walls of the box. These fingers are thrust in and drawn out by the swinging arms G², pivoted at g, the end of the upper arm G² engaging the operating-cam 75 G. These several parts are common in machines of this class and need no further detail description, as they form no part of my invention.

H is a cam for operating the forming die 80 or plunger T.

I is a hand-wheel mounted on the driving-shaft and is designed to provide means for operating the shaft when power is not applied to the pulley for the purpose of adjusting the 85 parts by giving the driving mechanism a slight movement.

J is one of a pair of feed-rolls commonly employed to feed the ribbon of paper to the box-forming mechanism. One roll lies directly under the other, and they are geared together by spur-gears, as shown at j, at one end of the shaft.

j' is a bevel-gear meshing with a similar gear on the shaft K, which is driven by 95 sprocket connection K' with the driving-shaft B. On the shaft K is an eccentric L, designed to give a reciprocating movement to the bar L', which has an operating engagement with the swinging arm M, pivoted to the frame of 101 the machine at m.

l is a link connection between the bar L' and that portion engaging the swinging arm M, providing a slight flexibility, necessary on

account of the bar L' having a movement tangent to the arc formed by the swinging of the arm M.

l' is a spring mounted on the rod engaging 5 the link connection, and l² is a nut for adjusting the tension of the spring. The object of this will be hereinafter explained.

N is a dog pivoted to the swinging arm and designed to engage the receiving-pockets P, 10 which are preferably grouped in series, forming a segment of a circle.

Q is a channel or circular way having a closed base designed to receive the segments containing the pockets P.

15 R is a knock-out plunger mounted in suitable hangers r, secured to the swinging arm M.

r' is a pin engaged with the knock-out plunger, on which is provided a friction-roll r².

R' is a cam secured to the annular channel 20 or way and is designed to force down the knock-out plunger when the operating-arm M, carrying the dog which engages the pockets, is moved forward by the rotation of the cam L. As the arm controlling the knock-out plunger passes under the cam R the box 25 contained in the pocket P registers with an opening (not shown) in the bottom of the channel-way Q and the box is thrown out.

Referring to Figs. 5 and 6 of the drawings, 30 S is a bolt sleeved in the framework of the machine and provided at its outer end with an upstanding pin S'. L² is a cam or wedge secured to the bar L'. p p are openings in the walls of the pockets P designed to receive the end of the bolt S to lock the pocket 35 in position under the forming-plunger T. S² is a spring engaging the end of the pin S', the tension of which is designed to draw the bolt into the opening p and the pin into operating 40 contact with the wedge L². t t are ways in which the forming-plunger T travels. This forming-plunger is made in two parts, the upper portion T' engaging the operating-cam H, the parts T and T' being connected together 45 by a threaded-bolt connection adjusted by the nuts T². The object of this adjustment, as has been heretofore suggested, is to provide means to take up the wear in the forming-die or to more accurately adjust the movement of the plunger with relation to the receiving-pockets.

It will be seen that when the cam L rotates and the bar L' is carrying the wedge L² it is thrust to the right, the wedge forcing the locking-bolt out of engagement with the aperture 55 in the pockets P, and when the arm L' starts on its backward movement, due to the movement of the cam L, the swinging arm M, on which is mounted the dog N, will engage one 60 of the pockets of the segments and move forward the series one point, or, in other words, the next successive pocket will be pushed into position under the forming-die, the adjustment of the several parts and the cam being 65 so constructed as to bring about this result. When it has reached this position, the locking-bolt is again engaging the pocket and

holding it in position until the forming-plunger T forces the paper down into the pocket and against the bottom wall of the channel-way Q. It will be seen that the spring l' insures a sufficient latitude of adjustment, so that when the pockets are moved forward the bolt S will be in position to drop into place the moment the opening in the pocket is directly in line with the end of the locking-bolt. 70

The operation of the device will be readily understood. The paper, which is in the form of a ribbon, is fed forward in the usual manner under the several gluing, slitting, and cutting mechanisms (which form no part of this invention) into position under the forming-plunger T. The operation of the cam H then moves the plunger and forces the paper into the pocket designed to receive it. After 80 the box is formed a further movement of the driving-shaft causes the cam L to rotate, thereby operating a connecting mechanism with the swinging arm M, on which the dog N is mounted, which serves to force forward the 85 next succeeding pocket into position under the forming-die, when the operation just described is repeated. When the first box formed reaches the position directly over an opening provided in the bottom of the channel-way, a suitable knock-out plunger—as, for instance, that shown at R—is provided to discharge the boxes from the machine, the time intervening between the formation of the box and its discharge from the pocket being of sufficient duration to admit of the box 90 being thoroughly dried.

While I have shown the pockets in segmental groups adapted to travel in a circular way, I would have it distinctly understood that I 95 contemplate the employment of single pockets which may travel in a straight or circular way as coming within the scope of my invention, one of the essential features of which is the provision of a channel or way having a 100 solid bottom against which the forming-die may operate.

Having thus described my invention, what I claim is—

1. In a box-machine, the combination of a 115 forming-plunger, a movable receiving-pocket, and a channel-way to guide the pocket to the plunger provided with a solid base below the plunger against which the plunger forces the paper in forming the box, substantially as 120 described.

2. In a box-machine, the combination of a forming-plunger, a sliding receiving-pocket, and a channel-way to guide the pocket to the plunger provided with a solid base below the 125 plunger to support the paper while the box is being formed, substantially as described.

3. In a box-machine, the combination of a forming-plunger, a plurality of receiving-pockets grouped together, and a channel-way 130 to guide the receiving-pockets to the plunger and provided with a solid base below the plunger to support the paper while the box is being formed, substantially as described.

4. In a box-machine, the combination of a forming-plunger, a fixed circular channel-way having a solid base below the forming-plunger to support the paper while the box is being formed, and receiving-pockets adapted to travel in said channel-way, substantially as described. 25
5. In a box-machine, the combination of a forming-plunger, a fixed circular channel-way having a solid base below the forming-plunger to support the paper while the box is being formed, and a plurality of receiving-pockets adapted to travel in said channel-way, substantially as described. 30
- 15 6. In a box-machine, the combination of a forming-plunger, a fixed channel-way having a closed base below the forming-plunger to support the paper while the box is being formed, receiving-pockets adapted to travel within said way, and means for moving said pockets successively under the forming-plunger, substantially as described. 35
- 20 7. In a box-machine, the combination of the forming-plunger, a channel-way, receiving-
- pockets adapted to travel in said way, a horizontal swinging arm, one end being pivoted to the frame of the machine, an eccentric L, means for connecting the eccentric with the swinging arm whereby the same may be operated, and a dog M mounted on said swinging arm to engage the pockets and force them successively forward when the swinging arm is operated, substantially as described. 40
8. In a box-machine, mechanism for automatically locking and releasing the receiving-pockets under the forming-plunger consisting of a spring-actuated sliding bolt S adapted to engage the pockets successively, an arm provided with a wedge-shaped portion to engage said bolt, and an eccentric for operating said arm, substantially as described. 45

In testimony whereof I sign this specification in the presence of two witnesses.

JOHN S. WOODBRIDGE.
